(57) **CLAIM**

The ornamental design for an optic protector cover, as shown and described.

DESCRIPTION

FIG. 1 is a perspective view of the optic protector cover showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a front elevational view thereof;

FIG. 7 is a perspective view thereof with the environment of a lens attached to the optic protector cover;

FIG. 8 is a front elevational view thereof with the environment of a lens attached to the optic protector cover; and,

FIG. 9 is another perspective view thereof with the environment of a lens detached from the optic protector cover. The broken lines depict portions of the optic protector cover that form no part of the claimed design. The broken lines in FIGS. 7-9 and the areas within them depict the environment of a lens that form no part of the claimed design.
